UNITED STATES PATENT OFFICE

ROBERT KRUSE, OF BERLIN, GERMANY, ASSIGNOR TO SIEMENS & HALSKE AKTIEN-
GESELLSCHAFT, OF WERNERWERK, SIEMENSSTADT, NEAR BERLIN, GERMANY

TELEPHONE SYSTEM

Application filed April 30, 1930, Serial No. 448,486, and in Germany June 12, 1929.

The invention relates to a circuit arrangement for party lines in communication systems, especially telephone systems.

One object is to effect without any special switching operation for that purpose, the marking engaged of the junction line immediately the latter is seized, this marking engaged being required to keep the conversation secret, and is effected by causing switching devices to function when the connecting line is seized, whereupon by transmitting alternating current they automatically prevent branch-off stations being connected to this connecting line.

15 Another object is to set up in the simplest manner a connection with other party lines over the calling party line. This is achieved in that a storer is associated with the party line, and when the stations call one another 20 the storer positions the switches at these stations, and when the designating number of another party line is selected it directly brings about the connecting up of the other party to the calling party line.

25 Another object is to effect uniformity in the construction of communication systems more especially telephone systems with storing devices by enabling the storing devices to be easily adjusted to the different damping 30 of the connecting lines (lines of different lengths) and to the types of switches used. This is achieved by providing the storer with switching devices, which enable an alteration to be effected in the speed at which the current impulses are given off by the storer.

Another object is to associate the party lines with a large number of subscribers' lines stations, without having to divide the latter into groups. This enables simple 40 switches and more especially small impulse senders (10 point number dials) to be used, thereby in the latter case are avoided great difficulties in connecting a party line to an exchange fitted with automatic connecting 45 devices built up on the decimal system, because the subscribers' stations can use their impulse senders in the same manner for calls in any direction. This is achieved in that the translator belonging to the party line 50 is positioned by number impulses, which have

a decimal grouping and are sent out from a calling subscriber's station for selecting a station belonging to the calling subscriber's line, and the said translator then gives off number impulses in uninterrupted succession for the purpose of reaching the wanted subscriber's station.

Another object is, when high value connections are to be set up and the party lines are engaged by low value connections, to compulsorily release the low value connection by disconnecting all the stations of the party line, in order to render the conversation secret. This is achieved in that after the seizing of a party line, which is already engaged by a low value connection, for a high value connection to a station of that line, switching means come into action and cause switches, which are located at each of the stations to be positioned into a resting position (normal or blocking position).

Other objects pertaining to the detailed circuit arrangement will be apparent from the following specification.

The invention is illustrated in the accompanying drawings, comprising Figs. 1 to 3, inclusive. The various sheets should be joined together, with Fig. 1 to the left of Fig. 2 and Fig. 3 to the right of Fig. 2.

Figs. 1 and 2 together show by means of the usual schematic diagram, the switching device in the exchange accessible to the party line serves to receive the current impulses transmitted by the calling subscriber as well as to store them up and to transform them; it also effects the sending back of the impulses into the party line for the purpose of connecting up the wanted subscriber, this being effected by operating the stepping switches individual to the different stations.

For this storing and translating are used for example two stepping switches; of these the storer 1, which is the first to be positioned, is constructed like a first preselector having 5 contact segments and therefore also 5 wipers *a, b, c, d, e*, and the storer 2 like a side switch likewise consists of 5 contact segments, which are insulated from one another and are bridged over by the wipers in the corresponding positions of the storer

when the latter is positioned. The wiring of the storers can easily be seen from the example shown. The running-off of the storer is effected by a relay chain, alternating current impulses being at the same time sent over the party line for connecting up the wanted subscriber.

The trunk exchange FA has access to the party lines and the relay C is energized in some manner to place the impulse receiving relay A under control of the trunk exchange FA by closing contact 147c. The impulse transmission for connecting up the wanted subscriber is effected in the same manner, by the trunk exchange FA, as the regular calls.

The line II shown in the upper part of Fig. 1 is another subscriber's party line similar to line VL.

Fig. 3 shows the party line subscriber's station equipment. In the present example stepping switches are provided at every subscriber's station. They can be controlled from the device fitted in an exchange accessible to the party line. The stepping switches at the different stations function in such a manner that when they leave their normal position they operate certain contacts and when they reach certain positions corresponding to the connected up stations they operate other contacts. At the subscriber's station T these contacts function in the following manner: The wiper 20s touches the contact segment as soon as the first step is taken; the wiper 6s leaves the contact segment for example at the last but one step, which in the present example is the 31st step; while the wiper 9s opens its contact as soon as it leaves the normal position; the other wipers 10s, 11s, and 17s only effect a circuit closure at the position of the stepping switch corresponding to the respective station.

The relays R, R1, etc., are shunted across the conductors a-b of connecting line VL and receive the alternating current impulses sent out from the device in the exchange, for stepping the rotary switches at each subscriber's station.

Subscriber's station T1 and any other subscriber's station on the line will have the same equipment as station T, but wired to different contacts of rotary switches.

Relay D is the rotary magnet for stepping the rotary wipers and W is the subscriber's bell which is cut out of circuit when the subscriber answers.

A call between two subscribers on the same party line

As an example of the invention will be described a connection between the subscriber T of a party line and the subscriber T1 of the same party line.

When the subscriber T takes down his receiver, the contacts of his switch-hook are

operated, that is to say the contacts 13hu and 15hu are opened and the contacts 14hu and 16hu are closed. The closing of contact 16hu energizes the relay U2 over: earth, contact 16hu, relay U2, wiper 9s of the stepping switch, contact 5j, wiper 6s of the stepping switch, relay J, battery, earth. For want of sufficient current the relay J is not operated in this circuit. On being energized the relay U2 closes the contacts 1u2, 2u2, 8u2, and 12u2; thereby the leads a and b of the connecting line VL are bridged over at the subscriber's station T and in addition the relay U2 is placed in a locking circuit. Thereupon the relay A located in the exchange accessible to the party line is energized over: earth, battery, winding I of relay A, contacts 141c, 21w1, 135x, lead a of the connecting line VL, contact 1u2, subscriber T, contact 2u2, lead b of the connecting line VL, contacts 133x, 23w1, winding II of relay A, earth. Relay A operates its contacts hence relay V is energized over: earth, contacts 29w, 30a, relay V, battery, earth. Thereupon the relay Z is energized over: earth, contact 31v, relay Z, battery, earth; and the relay U is energized over: earth, battery, rotary magnet D1 of the storer 1, wiper s1 of the storer 1, relay U, contact 91v, earth. In addition the relays S and R are energized over: earth, contact 80v, wiper 132s2 of the storer 2, windings I of the relays R and S, battery, earth. By closing its contact 56u, the relay U energizes the relay W1 over: earth, battery, relay W1, contacts 56u, 57u1, 58p1, 59v, earth. The relay W1 opens its contacts 21w1 and 23w1 and closes its contacts 22w1 and 24w1. The opening of the said contacts disconnects the relay A from the loop extending over the subscriber's station, and it therefore falls back. Thereupon the relay H is energized over: earth, battery, relay H, contacts 70q, 79v, 78a, 76w, earth. Upon being energized, the relay H closes a circuit for energizing the relay M over: earth, battery, winding II of relay M, contacts 62q, 63h, 65v, earth. By closing its contacts 26m and 28m, the relay M applies alternating current to the leads a and b of the connecting line VL, which operates the alternating current relays (R, R1) located at the different telephone stations. The energizing of relay R causes the relay J to be operated in the station T and in corresponding manner in the other stations, the devices for the latter are not shown here, as they correspond to those of the station T. The energizing circuit for the relay J extends in the station T over: earth, contacts 7r, 5j, wiper 6s of the stepping switch, relay J, battery, earth. Relay J now independently of the relay contact 7r holds itself over: earth, contact 4d of the rotary magnet D of the stepping switch, 3j, relay J, battery, earth. On being energized, the relay J at its contact 19j

operates the rotary magnet D of the stepping switch, which is moved on one step and therefore opens the contact at its wiper 9 s. Nevertheless the relay U 2 remains energized 5 because the contact opened at wiper 9 s is bridged over at contact 8 u 2 when relay U 2 is operated. As, however, at all the other stations except the calling station the relays corresponding to relay U 2 have not been 10 energized, it is impossible for the other subscribers of the party line to operate their relays U 2 with their switchhook by taking down the receiver, and thus it is impossible for them to connect themselves to the common 15 line. Hence the taking down of the receiver at the calling subscriber's station causes the automatic blocking of all other subscribers' stations belonging to the party line.

If we now consider the further circuit 20 changes in the exchange, will see that after the relay M has been operated and has caused the alternating current impulse to be sent out, the relay Q is energized over: earth, battery, relay Q, contacts 68 m, 65 v, earth. Relay Q places itself in a locking circuit over: earth, battery, relay Q, contact 69 q, 79 v, 78 a, 76 w. The opening of contact 70 q deenergizes the relay H, and the opening of contact 62 q deenergizes the relay M. Here it should 25 also be mentioned that upon the operation of relay M, the relay U 1 is also energized over: earth, battery, winding II of relay U 1, wiper 51 s 2 of the storer 2, contacts 54 m, 53 v, earth. Relay U 1 places its winding II in a 30 locking circuit, which extends over contact 52 u 1 after relay M has been released and has opened the contact 54 m. On being energized, the relay U 1 at contact 57 u 1 opens the circuit for energizing the relay W 1, hence 35 the subscriber's loop is again switched through to the relay A in the exchange. The relay is again operated and at contact 78 a deenergizes also the relay Q.

As we have seen at the transmission of the 40 alternating current impulse the relays H, M and Q operate in an energizing chain. These relays serve for impulse correction, because, owing to the long connecting lines, the relay A does not work with the required uniformity of impulse succeeded by pause. This 45 irregular working is corrected by the relays M, Q and H, and a uniform impulse relationship is created.

After the relay U 1 has been energized, the 50 relay D is operated over: earth, battery, differentially connected and parallelly located windings I and II of relay D, contacts 129 u, 130 u 1, 131 v, earth. Owing to its differential action, the relay D is operated slowly, the 55 delay being so adjusted that it is not operated until the correcting chain of relays M, Q and H has functioned once, the object being to prevent a premature actuation of the storers, the connecting up of the latter being dependent on contact 86 d of relay D.

After the stepping switches at the different telephone stations have been moved on, the relays A, V, Z, R, S, U, U 1 and D are therefore energized in the exchange. When the calling subscriber now transmits number impulses for the purpose of connecting up the wanted subscriber, he interrupts at each impulse the loop over the a and b leads of the connecting line, and thereby the relay A in the exchange is released and pulled up again 70 in accordance with the interruptions of the loop. The impulse correcting relays H, Q and M now work in accordance with the numerical selection sent out by the subscriber, and do so under the control of the impulse receiving relay A. The correcting chain of relays M, Q and H is controlled over the contact 78 a in the manner already described 75 in the description of the first alternating current impulse for moving on the stepping switches from their normal position. Thus by the contact 78 a is operated the relay H, by the relay H (contact 63 h) the relay M and by the relay M (contact 68 m) the relay Q; the latter then causes the entire correcting 80 chain to fall back by opening the contacts 62 q, 70 q, so that the relays can be again operated by the impulse contact 78 a. We see therefore that every relay of the correcting 85 chain is operated in accordance with the impulses of the impulse receiving relay A; hence also the storer 1, the rotary magnet D 1 of which is controlled by contact 87 q, is operated in accordance with the impulse 90 train transmitted from the subscriber. Therefore if the transmitted impulses consist of 4 impulses, they operate the rotary magnet D 1 of the storer 1 four times over: earth, battery, rotary magnet D 1 of storer 1, contacts 93 u, 85 u 1, 86 d, 87 q, 88 v, earth. Therefore 95 the storer 1 is positioned onto the fourth step as is shown in the drawing; it has already 100 been said that this storer corresponds to a known preselector.

The relay U falls back at the end of the first 105 train of impulses; during these impulses it was maintained energized over: earth, battery, resistance Wi 1, contacts 89 q, 90 u, relay U, contact 91 v, earth. On falling back the relay at its contact 92 u effects a switching 110 over from the rotary magnet D 1 to the rotary magnet D 2 of the storer 2; therefore the second impulse train, which is assumed to comprise 2 impulses, now acts on the rotary magnet D 2 of the storer 2 and twice operates it over: earth, battery, rotary magnet D 2 of the storer 2, contacts 92 u, 85 u 1, 86 d, 87 q, 88 v, earth. Accordingly the rotary magnet D 2 advances the storer 2 two steps, so that 115 its wipers bridge-over the step 2 in each segment, this being shown by dotted lines in the figure.

At the end of the second impulse train the relay U 1 falls back; during the second 120 impulse train it was maintained energized 125

over: earth, battery, winding I of relay U 1, contacts 55 *u* 1, 54 *m*, 53 *v*, earth. Thereupon the relay W is energized and owing to its two windings being differentially connected, like the relay D it is slowly operated over: earth, battery, parallelly located windings I and II of relay W, contacts 127 *u*, 57 *u* 1, 58 *p* 1, 59 *v*, earth. Furthermore the relay D is released by the opening of contact 130 *u* 1, and after the relay W has been operated, the relay W 1 is energized over: earth, battery, relay W 1, contacts 128 *w*, 58 *p* 1, 59 *v*, earth. The energizing of relay W causes the relay chain consisting of the relays H 1, H 2, H 3, H 4, H 5, and P to be started up for running off the positioned storer, and during this running off, alternating current is sent over the party line and the contacts of the relays W 1 and M for connecting up the wanted subscriber.

During the reception of current impulses transmitted by the subscriber, the relay A functioned as an impulse receiving relay, and during the running off of the storer it functions as a beating relay in the relay chain for sending impulses over the party line. In addition to the impulse correcting relays M, Q and H, there also functions now the relay O, which together work as impulse beating relay; and they do so in such a manner that the relays M, O, Q, and H by their interaction uninterruptedly determine the length of the opening and closing of the impulse circuit.

The speed of the impulses must be adjusted to the length of the lines and to the type of stepping switches used, so in order to obtain the simplest possible arrangement for adjusting the speed of the impulses, during the running-off of the storer, the relay O is provided with a second winding, which is short circuited at each impulse over a contact of this relay during the sending back of the impulses. The duration of the contact make can be increased or decreased in simplest manner for example by means of an adjusting screw on the contact 66 *o*, hence the duration of the short circuiting of winding II of relay O can be varied. This renders it easily possible to alter the giving of the impulses in accordance with the given conditions, so that for example in the present example this speed of impulse transmission can lie between the limits of 9 and 18 interruptions per second.

The interaction of the above-mentioned relays M, Q, H, and O is repeated to the relays A, B, D, and E, and this is done in such a manner that, as later described, the relays A, B, D and E in the beat operate for different lengths of time. It should also be mentioned that by means of the relay H, (contact 113 *h* and 114 *h*) the relay chain M, O, Q, and H acts on the relay chain A, B, D, and E, and with the aid of a contact of relay M (26 *m*

and 28 *m*), it sends current impulses over the party line.

The relays R and S, which, as already said, were energized as soon as the exchange was taken into use, place themselves in a locking circuit, thus the relay S is locked over its contact 84 *s* and winding I, while relay R is locked over its winding II by the contact 83 *r*.

The storer is run-off by the chain of relays H 1, H 2, etc. in the following manner: After the relay W has been operated, the relay H 1 is energized over: earth, battery, relay H 1, contacts 98 *h* 2, 96 *e*, 95 *h*, 94 *w*, earth. The relay H 1 places itself in a locking circuit over: earth, battery, relay H 1, contacts 100 *h* 1, 109 *p*, 110 *v*, earth. The operating of relay H 1 causes the relay H to be energized over: earth, contacts 77 *w*, 75 *h* 1, 74 *p* 1, 73 *p*, 72 *o*, 70 *q*, relay H, battery, earth. The closing of contact 114 *h* energizes the relay A over: earth, battery, winding III of relay A, contacts 112 *w*, 125 *b*, 114 *h*, 117 *p* 1, 118 *p*, 119 *v*, earth. The energizing of relay H causes the relays M, Q and O to be energized in succession as has already been described for the relays M and Q when the number impulses were received. After they have mutually controlled each other, they again release relay H, so that the opening of contact 114 *h* causes the relay B to be energized over: earth, battery, winding III of relay A, contacts 112 *w*, 125 *b*, winding II of relay B, contacts 115 *a*, 117 *p* 1, 118 *p*, 119 *v*, earth. Relay A remains energized in this circuit, while at the same time the closing of contact 126 *b* establishes a locking circuit for relay B over winding I.

An alternating current impulse is sent over the party line the first time the relay H is operated, because the contacts 28 *m* and 26 *m* are closed by relay M when the latter is energized over contact 63 *h* by relay H. At the same time the test relay P 1 over contact 34 *h* is applied to the odd steps of the contact segment 1 of the storer 2, the circuit extending over: contacts 39 *r*, 36 *b*, 35 *u* 1, 34 *h*, relay P 1, battery, earth.

The second alternating current impulse is sent out the second time the relay H is operated, while at the same time the test relay P 1 is applied to the even steps of the contact segment 1 of the storer 2, because now the relay B, which was energized the first time the relay H fell back, has now closed its contact 37 *b*, namely over: segment 1 (even steps), contacts 40 *r*, 37 *b*, 35 *u* 1, 34 *h*, relay P 1, battery, earth. As no potential has been applied to the contact segment 1 of the even and odd steps, the relay P 1 is not energized.

The second time the relay H pulls up, the relay A is released owing to the opening of contact 113 *h*.

The relays D and E work under the control of relay A in the same manner as relays A

and B work under the control of relay H because the first time the relay A pulls up and therefore also the first time relay H pulls up, the relay D is energized over: earth, contacts 119 v, 118 p, 117 p 1, 121 a, 122 e, 124 w, winding III of relay D, battery, earth. The first time relay A falls back (that is the second time relay H pulls up) the relay E is energized over: earth, contacts 119 v, 118 p, 117 p 1, 116 d, winding I of relay E, contacts 122 e, 124 w, winding III of relay D, battery, earth. Relay E places its winding II in a locking circuit over contact 123 e.

When relay H falls back for the second

time, relay H 2 is energized over: earth, battery, relay H 2, contacts 102 h 3, 97 e, 95 h, 94 w, earth. The locking circuit of relay H 2 extends over: earth, battery, relay H 2, contacts 101 h 2, 109 p, 110 v, earth. In addition, the relay B is deenergized by the opening of contact 114 h.

When the relay H is energized for the third time, as at the first energizing the test relay is applied to the odd steps in the segment 1 and in similar manner the relay A is energized, which by opening its contact 120 a now deenergizes the relay D.

When the relay H falls back for the third time, the relay B is operated like at the first deenergization and it closes its contact 37 b, hence the fourth time the relay H pulls up the test relay P 1 tests the even steps of segment 1.

When the relay H is energized for the fourth time, the relay A falls back like it did at the second energizing of relay H, therefore also the relay E is deenergized by the opening of the contact 121 a.

The fourth time relay H falls back, the opening of the contact 114 h deenergizes the relay B and also energizes the relay H 3 over: earth, battery, relay H 3, contacts 104 h 4, 99 h 2, 96 e, 95 h, 94 w, earth. The relay H 3 locks itself over its contact 105 h 3.

When the relay H is energized for the fifth time, the just-described operations for the relays A, B, D, and E are repeated, so that at the sixth release of relay H the relay H 4 is energized and at the eighth release the relay H 5 is energized, these relays placing themselves in corresponding locking circuits.

At the ninth energizing of relay H, the relay A is again energized and thus also the relay D.

At the ninth release, the relay B is energized in the manner already described; hence at the tenth energizing of relay H the test relay P 1 is connected for the tenth time to the segment 1. At the same time the relay A is deenergized and then again causes the relay E to be energized. The tenth time relay H falls back, it causes the relay P to be energized over: earth, battery, relay P, contacts 108 h 5, 108 h 3, 97 e, 95 h, 94 w, earth. The relay P operates its contacts and thus brings

about the following circuit changes: The opening of contact 73 p brings the relay chain H, M, Q, O into the initial condition, in the same manner as the relays H 1, H 2, H 3, H 4, H 5 by the opening of contact 109 p. The opening of contact 118 p also brings the chain of relays A, B, D, E into the normal position. In addition the locking circuit of relay R is opened by the contact 82 p. During the momentary opening, the relay S holds up owing to its winding II being short circuited. The closing of the contacts 38 r and 41 r prepares the test circuit for the relay P 1 for the segment 2.

After the relay P has also fallen back when relay E has been deenergized, the operations are repeated in the same manner at the segment 2. 10 impulses are transmitted again by five times testing the even and odd steps of segment 2. After they have run off, the energizing of relay P again causes the relays H 1—H 5 of the relay chain to be deenergized. The relay S is now also deenergized, because it does not act slowly when contact 82 p is opened, as the short circuit has been removed by the contact 81 r. Therefore the closing of contacts 42 s and 44 s places the relay P 1 at the disposition of segment 3 of the storer 2. Also at the running over of the odd steps in segment 3 for the first time, the relay P 1 is not yet operated, because, although the relay H 1 has already closed its contact 46 h 1, the first step has not been bridged over. This only occurs when the relay H has been operated for the second time, that is to say at the second impulse after the segment 3 has been reached when the even steps are being tested and then an energizing circuit is closed over the bridged step 2. This circuit extends over: earth, contact 46 h 1, storer 1, step 2 (storer 2), contacts 44 s, 41 r, 37 b, 34 h, relay P 1, battery, earth. By closing its contact 32 p 1, relay P 1 places itself in a locking circuit and so by opening contact 74 p 1 prevents the relay H being again energized and thus also prevents the common relay chain being energized again; hence no more alternating current impulses are sent over the party line. Furthermore the relays A, B, D, E are deenergized by the opening of contact 117 p 1.

We can see from the description that there are transmitted ten impulses when segment 1 is run over, ten more impulses are transmitted for segment 2 and two impulses for segment 3, thus a total of 22 impulses in place of the subscriber's numerical selection 4, 2 are transmitted. The 22 impulses move on all the stepping switches 22 steps, but in the position 22 only at the wanted station are closed the corresponding contacts, so that the contact corresponding to the wiper 17 s closes a circuit for the bell W to call the subscriber. On taking down the receiver, the closing of the contact at the wipers corresponding to

120
125
130

the wipers 10 *s* and 11 *s* causes the energizing of the relay corresponding to the relay U 2, thus bringing about the connecting up of the wanted subscriber.

5 The already-described energizing of relay P 1 causes the relays W and W 1 to fall back when the contact 58 *p* 1 is opened, hence the closing of the contacts 21 *w* 1 and 23 *w* 1 causes the speaking connection to be fed over the impulse receiving relay A.

10 When the subscriber's loop is opened at the end of the conversation, relay A falls back and after a little while effects the release of the slow-acting relay *v*, which after a while causes the very slow-acting relay Z to fall back. During the interval between the falling back of relay V and the release of relay Z a circuit is established for the relays M and W 1 over: earth, contacts 60 *z*, 61 *v*, windings 20 I of the relays M and W 1, battery, earth. The closing of the contacts 22 *w* 1 and 24 *w* 1 as well as contacts 26 *m* and 28 *m* causes alternating current to be applied to the party line, thereby bringing about the return of the 25 step-by-step switches. The storers 1 and 2 are also returned to their normal position in some manner of no interest here.

30 *A call from a subscriber on one party line to a subscriber on another party line*

If the subscriber had influenced the storer 1 by means of one impulse instead of 4, a circuit for the relay X would have been established after the impulse transmission and it 35 would have extended over: earth, contact 138 *z* II, relay X, arrow 2 (step 2, segment 4), wiper of arrow 1, point *o*, resistance W *i* 2, contacts 137 *u* 1, 92 *u*, rotary magnet D 2 (not 40 operated), battery, earth. By opening its contacts 133 *w* and 135 *w*, the relay X disconnects the relay A from the calling subscriber's station and switches the latter over to the 45 impulse receiving relay of the other traffic direction (line II). Relay A is maintained energized over the contact 149 *w*. Relay P 1 is maintained energized over the closed contact 148 *w*, and prevents the storer running-off. The energizing of the impulse receiving relay in line II, which corresponds to the relay 50 A, brings about the same operations as took place when relay A was energized, namely one energization of the relay corresponding to the relay V, and thereby an energization of the relay corresponding to relay Z, hence the 55 relay X is maintained energized over earth, contacts 150 *z* II, 139 *v* II, 140 *w*, relay X etc. as already described for the energization of the relay X.

60 The impulse trains subsequently transmitted then influence switching devices on the other line.

65 The release takes place in such a manner that first of all upon the release of the impulse receiving relay in line II there takes place the same circuit changes as when relay

A was deenergized; that is to say, the relay in line II corresponding to the relay V is first deenergized, and by opening the contact 139 *v* II it releases the relay X, which at contact 149 *w* opens the locking circuit of relay A, 70 hence the already-described release is thereby brought about.

Toll offering service

If the party line seized as described for a 75 low value connection is reached by the trunk exchange FA for setting up a high value connection, the trunk exchange on reaching the party line will over the leads *a* 1 and *b* 1 notify the subscribers that there is a high value 80 connection to be set up. By applying an earth to the lead *c* 1, the relay C is energized, which by closing its contact 147 *c* connects winding I of relay A to the lead *a* 1 and by closing the contact 146 *c* connects the relay T 85 to that lead.

In some manner or other the trunk exchange now gives over the lead *a* 1 an earth current impulse, whereby the relay T is energized and at contact 143 *t* it opens the locking circuit 90 of the relay A. Thereby the relay V is deenergized (by the opening of contact 30 *a*), and as the very slow-acting relay Z is still energized, it brings about the release of all the stepping switches because a long alternating current impulse is sent into the party line owing to the relays M and W 1 being energized over: earth, battery, windings I of the relays M and W 1, contacts 61 *v*, 60 *z*, earth. The alternating current impulse for 100 some time operates the relays R, R 1, etc. therefore the J relays are energized over: earth, battery, relay J, wiper 6 *s*, contacts 5 *j*, 7 *r*, earth. Relay J with its contact 19 *j* operates the rotary magnet D, which at its contact 4 *d* interrupts the locking circuit of relay J; thus the relay J and rotary magnet D interact. This continues until the wiper 6 *s* leaves the contact segment at the 31st step, so 105 opening the circuit for energizing the relay J. 110

If the subscriber T has not yet hung up the receiver, the stepping switch of the subscriber T remains in the position 31, which is the blocking position. If the receiver has already been hung up, the relay J is maintained energized over: earth, contacts 7 *r*, 13 *hu*, position 31 of the wiper 6 *s*, relay J, battery, earth, until the end of the alternating current impulse, and only then is relay J deenergized while at the same time the energizing circuit of the rotary magnet D is opened, whereupon this rotary magnet moves on the stepping switch into the initial position.

As soon as the compulsory release has 125 been effected, that is to say when relay T has fallen back, the relay A is energized over leads *a* 1 and *b* 1 looped in the trunk exchange FA, whereupon an alternating current impulse is sent out for blocking the 130

party line for other calls in the same manner as when this is done by the energizing of relay A when a subscriber's station of the party line originates a call.

5. What is claimed is:

1. In a telephone system, a party line having a plurality of subscribers' stations, a switching device individual to said party line and capable of transmitting an impulse over said line, and means responsive to an impulse from said switching device for automatically preventing the said subscribers' stations from seizing said party line.

2. In a telephone system, a party line having a plurality of subscribers' stations, a switching device individual to said party line and capable of transmitting an impulse over said line, means responsive to one of said subscribers' stations seizing said party line for said switching device to send an alternating current impulse over said line, and means responsive to said impulse for preventing any other subscribers' stations on said line from connecting thereto.

25. 3. In a telephone system, a party line having a plurality of subscribers' stations, a switching device individual to said party line and capable of transmitting alternating current impulses over said line, a relay mechanism and a stepping switch individual to each of said subscribers' stations and all responding in synchronism to alternating current impulses from said switching device for selecting the wanted subscriber's station.

35. 4. In a telephone system, a party line having a plurality of subscribers' stations, means responsive to one of said subscribers' stations seizing said party line for sending an alternating current impulse over said line for preventing any other subscribers' stations from being connected thereto, and means responsive to said subscriber's station dialling the number of another subscriber's station on said line for sending out alternating current impulses for connecting said other subscriber's station thereto.

45. 5. In a telephone system, a party line, individual switches for the stations on said line, means at the exchange for registering a number dialled by one of the stations, a sender controlled by the registering means for transmitting impulses back over the line to operate said switches, said sender including interrupter relays for generating impulses, and means for regulating the restoring time of one of said relays to adjust the rate at which impulses are transmitted.

55. 6. In a telephone system, a party line having a plurality of subscribers' stations, a switching device individual to said party line having digit register switches, means operative subsequent to said digit registers being positioned by groups of impulses from a subscriber's station on said party line for transmitting in uninterrupted succession the

number of impulses for selecting the wanted subscriber's station.

7. In a telephone system, a party line having a plurality of subscribers' stations, a relay mechanism and a stepping switch individual to each of said subscribers' stations, a switching device individual to said party line for transmitting impulses over said line and for registering the called subscriber's number, means responsive to one of said subscribers' stations seizing said party line for causing said switching device to send an impulse over said line to operate said stepping switches at all of said subscribers' stations to prevent other subscribers from seizing said party line, means operative subsequent to the registration of the called number for sending a series of impulses corresponding to the setting of the digit register to operate all of said stepping switches in synchronism, means responsive to the operation of said switches for signalling only the called station, and means responsive to the answering of the called party for connecting the called station to said party line.

8. In a telephone exchange, a party line having a plurality of subscribers' stations, a switching device individual to said party line and capable of transmitting alternating current impulses over said line, another telephone exchange having access to said switching device and said party line, a busy subscriber's station on said party line, means responsive to a call from said other exchange for disconnecting said busy subscriber's station, and means operative subsequent to said busy subscriber hanging up his receiver for selecting the wanted subscriber on said party line.

In witness whereof, I hereunto subscribe my name this 12th day of March, A. D. 1930.

ROBERT KRUSE.
